DISPLAY FORM

Stephen G. Allan, Kansas City, Mo.

Application September 20, 1934, Serial No. 744,770

3 Claims. (Cl. 223—68)

This invention relates to display forms and more particularly to those of the character employed in displaying coats, shirts, and similar garments, and has for its principal object to provide a form of simple, inexpensive construction, which can be readily fitted to a garment without use of padding.

In accomplishing this and other objects of the invention, as hereinafter pointed out, I have provided improved details of structure, the preferred form of which is illustrated in the accompanying drawing, wherein:

- Fig. 1 is a perspective view of a display form embodying the features of the present invention.
 15 Fig. 2 is a perspective view of the form showing the back section thereof in disassembled spaced relation from the front section.
 Fig. 3 is a vertical section through the center of the form.
 20 Fig. 4 is a horizontal section through the form on the line 4—4, Fig. 3.
 Fig. 5 is a detail section through the shoulder portion of the form particularly illustrating the hinge connection between the front and back sections.

25 Referring more in detail to the drawing:
 1 designates a display form including front and back body sections 2 and 3 preferably formed of paper board or other light material molded or 30 pressed to a shape simulating a human torso and having sufficient wall thickness to be self-supporting.

The front section preferably includes an integral neck portion 4 extending upwardly from 35 shoulder portions 5 and 6. The neck portion 4 is shaped to simulate the neck of a person and has the rear half 7 offset outwardly from the plane of the side edges 8 and 9 of the section. The side edges 8 and 9 extend downwardly under 40 the arm portions 10 and 11 to cooperate with the corresponding edges 12 and 13 of the back section 3. The shoulder portions 14 and 15 of the back section register with the corresponding portions 5 and 6 of the front section at opposite 45 sides of a back neck portion 16 which registers with the outset part 7 of the neck portion 4 of the front section. The lower parts 17 and 18 of the front and back sections terminate in a horizontal plane corresponding to a plane extending 50 through the hips of a torso and the front section is provided with a central notch 19 through which the adjustments are made to the form, as later described.

Fixed within each section at approximately the 55 waist line 20 thereof are horizontally positioned

stiffening members 21 and 22 respectively having aligning edge faces 23 and 24 located so that the face 23 is inset from the plane of the side edges 12 and 13 and face 24 is outset from the side edges 12—13 of the form sections in order 5 that the extended part of the member 21 forms a guide slidably engaged with the side edges of the rear form sections.

The front section of the display form is preferably supported for vertical adjustment on a 10 pedestal 25 including a base 26 having an upwardly extending post 27 terminating in a reduced extension 28 forming a stop shoulder 29 at the upper end of the post.

The reduced extension projects through a bearing opening 30 in the front stiffening member 21 and carries a stop collar 31. The stop collar 31 is adjustably fixed on the extension and in engagement with the under face of the stiffening member by means of a thumb screw 32 that is 20 threaded through the collar and engages the post extension. It is thus apparent that the form may be adjusted for height relatively to the base of the pedestal by loosening the set screw and sliding the collar along the post extension until 25 the form is at the desired height when the set screw is again retightened. Downward movement of the form is, however, limited by the stop shoulder 29 when the collar 31 engages therewith to prevent the bottom of the form sections from 30 striking the floor or other support on which the pedestal is resting.

The back section is suspendingly hinged from the shoulder and neck portions of the front sections by flexible shoulder straps 33 having their 35 ends 34 and 35 fixed to the adjacent shoulder portions 5—14 and 6—15 of the sections and by a flexible neck strap 36 having its ends 37 and 38 fixed respectively to the projecting parts 7 of the neck portion 4 of the front section and to the 40 underlying neck portion 16 of the back section. It is thus obvious that the neck strap 36, while allowing hinging movement of the back section retains the edges of the shoulder portions of the sections in registry with each other.

In the display form thus far described, the shoulder and neck portions will fill out and adequately support the neck and shoulder portions of a garment displayed thereon, but it happens that the lower portions of the garment rarely fit 50 the form. I, therefore, provide means for expanding or spreading the bottom part of the sections away from each other, while the shoulder straps act as hinges.

In accomplishing this adjustment, the faces 23 55

and 24 of the stiffening members 21 and 22 are recessed as at 39 and 40 to accommodate channel shaped brackets 41 and 42 so that the flanges 43 and 44 thereof overlie the top and bottom faces 5 of the stiffening members as shown in Figs. 2 and 3, the brackets being secured by suitable fastening devices such as screws 45.

Projecting upwardly from one of the flanges of each bracket are spaced pairs of ears 46, one 10 pair of which carries guide pins 47 that are slidably mounted in openings 48 in the other pair of ears whereby the pins cooperate with the neck strap 36 in supporting the sections in horizontal registry with each other.

15. In order to spread the sections apart, I provide a screw shaft 49 having one end threaded in one of the brackets 42 and carrying a knurled head 50 on its other end which is provided with a sleeve portion 51 rotatably anchored in the other bracket 20 41 so that when the head is rotated in one direction, the shaft is threaded into the bracket 42 to draw the sections together, and when it is rotated in the opposite direction, the shaft is threaded therefrom to spread the lower ends of 25 the form sections, the stiffening members being provided with sockets 52 and 53 to accommodate the ends of the shaft.

In order to slightly fill out the sleeve openings at the shoulder portions of a garment, the form 30 section is provided with disks 54 and 55 having convex outer faces 56 adapted to extend within the sleeves and flat inner faces to engage the arm portions of the other section. In the illustrated instance, the disks are shown attached to 35 the front form section so that substantially half of their diameters project from the side edges 8 and 9 to overlap the corresponding edges 12 and 13 of the rear section.

In using a form constructed and assembled as 40 described, the garment to be displayed, for example, a coat, is applied thereon with the form sections in collapsed condition. The screw shaft 49 is then operated by extending the hand through the notch 19 and manipulating the knurled head 45 50 with the fingers to spread the sections apart so that they snugly fit the garment. The form can also be adjusted for height through the notch 19, by positioning the collar 31 on the post extension 28.

50. From the foregoing, it is obvious that I have provided a display form which is of simple, inexpensive construction and which can be readily adjusted to the garment displayed thereon.

What I claim and desire to secure by Letters 55 Patent is:

1. A display form consisting of a front section

and a rear section hingedly connected together at their upper edges, the rear section having a curved recess in its upper edge, the front section being formed to constitute an integral front body portion and an unbroken collar portion projecting 5 rearwardly therefrom, the rear of the collar portion fitting in said recess at the upper edge of the rear section to cooperate therewith without interfering with the hinged connection between said sections, and means for adjustably connecting the 10 sections to expand and contract the same relative to each other for garment fitting purposes.

2. A display form simulating a torso divided longitudinally at the sides and top to form single-piece front and rear sections hinged together at 15 the top at opposite sides to permit relative swinging movement of the sections toward and from each other, the rear section having a recess in the upper edge and the front section being provided at the top with an integral unbroken cylindrical 20 neck merging into and forming a continuation of the front section and having its rear portion extended rearwardly beyond the front section and fitting the recess at the upper edge of the rear section, means for adjustably connecting the 25 sections to expand and contract the display form and distend a garment placed thereon, said form engaging the garment interiorly at the top and bottom thereof whereby the garment is caused to assume by a single adjustment of the sections 30 its predetermined style or pattern without the necessity of padding the form to fill out the garment, and supporting means for the form connected therewith solely at the waistline thereof thereby leaving the interior of the form above 35 the waistline unobstructed.

3. A display form simulating a torso divided longitudinally at the sides and top to form front and rear sections hinged together at the top to 40 permit relative swinging movement of the sections toward and from each other, one of the sections having a recess in the upper edge and the other section provided at the top with an integral unbroken substantially cylindrical neck merging into and forming a continuation of said 45 section and having a portion projecting beyond said section and fitting into the recess of the upper edge of the other section, and means for adjustably connecting the sections to move said sections toward and from each other for expanding and contracting said form and to distend a garment that is placed on said form whereby the garment is caused to assume by a single adjustment of the sections its predetermined style 50 or shape.

STEPHEN G. ALLAN.
